Patented Nov. 28, 1961

191,856

COMBINED TONGS AND SHOE HORN

James Postich, 569 Poland Center Road, Poland, Ohio

Filed Mar. 16, 1961, Ser. No. 64,407

Term of patent 14 years

(Cl. D86—10)

FIGURE 1 is a perspective view of a combined tongs and shoe horn, showing my new design, in partially open condition;

FIGURE 2 is a similar view thereof, in inverted position and in closed condition.

I claim:

The ornamental design for a combined tongs and shoe horn, as shown.
